UNITED STATES PATENT OFFICE.

JOHN GAMBLE, OF PHILADELPHIA, PENNSYLVANIA, ASSIGNOR TO GEORGE A. REACH,
OF PHILADELPHIA, PENNSYLVANIA.

FOOT-BALL.

985,893.

Specification of Letters Patent. Patented Mar. 7, 1911.

Application filed March 14, 1910. Serial No. 549,073.

To all whom it may concern:

Be it known that I, JOHN GAMBLE, a citizen of the United States, residing at Philadelphia, in the county of Philadelphia and 5 State of Pennsylvania, have invented new and useful Improvements in Foot-Balls, of which the following is a specification.

My invention relates to foot balls, and pertains more particularly to improvements 10 in articles of said class by which the inner bladder and the outer case are combined.

The object of my invention is to provide a foot ball in which the separate inner case or bladder is eliminated, the material of the 15 single case being saturated and coated on the inside with pure india-rubber gum, and the outside being likewise coated with such substance or a composition thereof to prevent puncture.

20 A further object of my invention is to provide a foot-ball of a single impervious air-tight case having the usual vent and lacing means employed in outer cases of ordinary construction, said vent being covered

25 with an inner patch of similar air-tight material suitably secured on the inner side of the case, and having an inflating tube adapted to be tucked in the pocket between said patch and the case, and laced therein in 30 closing the vent; and a still further object thereof is to provide a more simple, cheap and efficient article of said class than has heretofore been produced.

In the accompanying drawings illustrating my invention, in which like reference numerals indicate similar parts, Figure 1 is a perspective view of my foot ball with the vent open, and Fig. 2 is a sectional view of the same showing the vent closed, taken on 40 line 1—1 of Fig. 1.

Referring now to the drawings, 1 indicates a foot ball of the usual oval form, having a longitudinal vent 2 intermediate of its ends adapted to be laced through the 45 eyelets 3 by the cord 4. Said ball is made of a single case 5 of flexible fabric, the inner side of which is saturated and coated with a layer of india-rubber gum 6 to render it air tight, and the outside may be coated with 50 a similar material, or a composition thereof, adapted to render same impervious to puncture in ordinary use.

As shown in the drawings, the vent 2 is covered on the inside of the case with a patch 6 of similar material to that of which 55 the case is made, which is cemented or vulcanized adjacent to its outer edge to the inside of the ball to form an air-tight closure. Said patch 6 is provided with a flexible tube 7 adapted to protrude through the vent 2 60 for inflating the case, and may be tucked in the pocket 8 formed between the case 5 and the patch 6 and laced therein with the cord 4 through the eyelets 3 adjacent to the edge of the vent. 65

The construction and operation of my invention will be readily understood from the foregoing description and by reference to the accompanying drawings, and it will be appreciated that same may be varied 70 within a wide range from the specific exemplification thereof shown, without departing from the spirit and scope thereof.

Having thus described my invention, what I claim as new and desire to be secured by 75 Letters Patent, is—

1. A foot ball comprising a single case of flexible air-tight material, having a vent therein adapted to be laced together, a patch of air-tight material secured upon the inner side of said case adjacent to the edges of said vent and forming a free space or pocket between the edges of the case and patch, and a flexible tube attached to said patch communicating with the interior of 80 the case through same, adapted to be tucked in said pocket after inflation of the ball. 85

2. A foot ball comprising a single case of flexible fabric, having a vent therein, said fabric being coated on its inner side 90 with india-rubber gum to prevent the escape of air, a patch of similar material secured upon the inner side of said case to close said vent, a flexible tube communicating with the interior of said case through 95 said patch, and an outer coating of rubber upon said case, substantially as described.

In testimony whereof, I have hereunto signed my name to this specification in the presence of two subscribing witnesses.

JOHN GAMBLE.
